(57) **CLAIM**

We claim the ornamental design for the holder for cord for earphones and headphones, as shown and described.

DESCRIPTION

FIG. 1 is a front elevational view of the holder for cord for earphones and headphones;

FIG. 2 is a top plan view of the holder for cord for earphones and headphones;

FIG. 3 is a bottom plan view of the holder for cord for earphones and headphones;

FIG. 4 is a right side elevational view of the holder for cord for earphones and headphones;

FIG. 5 is a left side elevational view of the holder for cord for earphones and headphones;

FIG. 6 is a perspective view of the holder for cord for earphones and headphones; and,

FIG. 7 is a referential view of the holder for cord for earphones and headphones showing the article in use.

The broken line portions of the figures is included to show unclaimed subject matter only and forms no part of the claimed design.
